SPOOL

Walter L. Rutkowski, St. Louis, Mo., assignor to
 R. C. Can Company, St. Louis, Mo., a Corporation of Missouri

Application October 2, 1931. Serial No. 566,495

7 Claims. (Cl. 242—119)

My invention relates to spools, and, more particularly to spools made from pasteboard; and, it has for an object to provide a spool light in weight, strong and highly efficient for the purpose intended.

A further object of the invention is to provide a spool wherein the tubular body portion and the flanges are rigidly connected.

A still further object of the invention is the provision of a spool which possesses advantages in points of simplicity and efficiency, and, at the same time proves itself comparatively inexpensive in cost of manufacture.

With the above and other objects in view, the invention consists in the novel features of construction, arrangement and combination of parts hereinafter more fully described and finally pointed out in the claims hereto appended.

Referring to the accompanying drawing forming a part of this specification wherein like characters of reference denote similar parts throughout the several views:

Fig. 1 is a view partly in side elevation and partly in sectional elevation of a pasteboard spool and showing a facing ring member at each end thereof before it has been rolled into final position.

Fig. 2 is a view partly in side elevation and partly in sectional elevation of the spool showing the facing devices rolled into final position and one of the pasteboard flanges in contact with one of the end facing devices, but not fixed thereto.

Fig. 3 is a view of the spool partly in side elevation and partly in sectional elevation showing the flanges secured to the spool.

Fig. 4 is a sectional elevation of one of the spool flange retaining rings.

Fig. 5 is a plan view of one of the pasteboard flanges for the spool.

Referring to the drawing, 1 designates a tubular member, preferably made from spirally laminated pasteboard, although not necessarily limited thereto, to the ends of which are connected pasteboard flanges 2, as will be hereinafter described.

Adapted to be secured to each end of the tube 1 is a metallic facing device having a ring like wall 3 terminating at its one end in a right angular flange 4, as shown at the left side of Fig. 1, before it is finally fixed to the end of the tube.

The ring wall 3 of the facing device is receivable within the end of the tube and snugly fits

into the end of the tube initially. After the facing devices are applied to the tube, as shown in Fig. 1, the ring wall 3 is rolled and pressed outwardly into tight frictional contact with the inner face of the tube material and the flange 4 is rolled into the outer face of the tube material, thereby firmly locking the metallic facing devices to each end of the tube 1, as will be apparent from Fig. 2, thereby providing a metallic end facing therefor.

The pasteboard flanges 2, one of which is to be securely connected to each end of the tube 1, are provided with a central opening 5 so that the spool can be mounted upon a suitable spindle 6, as illustrated in Fig. 3.

The pasteboard flanges 2 are connected to the ends of the tube 1 in contact with the end face of the facing rings, as clearly shown in Fig. 3. In Fig. 2, I have shown one of the flanges 2 in position before it is connected to the end of the tube, as shown in Fig. 3.

The means for securely locking the flanges to the end of the tube 1 comprises a metallic locking device, or members embodying a ringlike wall 7 and a right angular flange 8 formed at one end of the ringlike wall 7, as shown in detail in Fig. 5.

After the flange 2 has been applied or mounted in contact with one of the facing devices, a locking device is applied by forcing the ringlike wall 7 thereof through the opening 5 of the flange and into the tube 1 so that the outer face of the ringlike wall 3 of the locking device is in frictional contact with the inner face of the ringlike wall 3 of the facing device.

After the locking device has been thus applied, the ringlike wall of the locking device is rolled or otherwise suitably pressed outwardly into tight frictional contact with the wall of the facing ring and the flange 8 of the locking device is brought into tight frictional contact with the outer face of the pasteboard flange 2, thereby securely holding the pasteboard flange in locked relation with the end of the tube.

From the foregoing description, it is evident that I provide a light, strong and comparatively inexpensive spool upon which wire, ribbon or any other suitable material may be wound.

The many advantages of the herein described invention will readily suggest themselves to those skilled in the art to which it appertains.

From the foregoing description, it is evident that a simple device for this purpose has been disclosed, but it is to be understood that I do

not desire to restrict, or limit myself to the very details of the construction shown and described, which is merely illustrative, it being obvious that changes, not involving the exercise of invention, may be made without conflicting or departing from the spirit of the invention within the scope of the appended claims.

What I claim is:

1. As an article of manufacture, a spool comprising a cylindrical spool body, metallic facing devices each having a flange rolled into locked engagement with the outer face of the tube at each end thereof, a pasteboard flange in contact with the end face of each facing device and a locking device having a portion thereof passing through a central opening in each flange and pressed into frictional contact with the tube facing devices and having a flange for pressed engagement with the outer face of the flange.

2. As an article of manufacture, a spool comprising a cylindrical spool body, metallic facing means applied to the ends of the tube, a flange having a central opening mounted upon the end face of each facing means and metallic locking means having a ring like wall adapted to pass through the central opening of each pasteboard flange and provided at its outer end with a flange, the ringlike wall of said locking device being pressed outwardly into frictional contact with the facing means within the tube and the flange of the locking device being pressed into frictional contact with the outer face of the pasteboard flange at each end of the tube to prevent displacement of the pasteboard flanges.

3. In a spool construction, a tubular body, a ring like device having a peripheral edge fixed to each end of the tubular body by rolling the device into engagement with the inner end and outer faces of the tubular body to provide a rolled facing for each end of the tubular body, a disk having a central opening mounted upon the rolled facing at each end of the tubular body and a pair of devices each having a pasteboard flange in contact with the outer faces of

the disk and said devices being secured to the tube facings by friction contact therewith within the tube.

4. In a spool construction, a tubular paper body, a metallic facing ring member secured to each end of the tubular body and engaging the inner, outer and end faces thereof, a flanged ring carried at each end of the tubular body and in frictional contact with the inner faces of the facing ring members and a disk for each end of the tubular body, said disks each having a central opening for receiving the flanged rings to mount said disks between the metallic facing ring members and the flanges of the rings.

5. In a spool construction, a tubular paper body, a metallic facing ring member secured to each end of the tubular body and engaging the inner, outer and end faces thereof, a flanged ring carried at each end of the tubular body and in frictional contact with the inner faces of the facing ring members and a disk for each end of the tubular body, said disks each having a central opening for receiving the flanged rings to mount said disks so that the facing ring members will prevent inward displacement of the disks and the flanges of said flanged rings prevent outward displacement of the disks.

6. In a spool construction, in combination, a cylindrical tubular body, flanged metallic facing rings applied by frictional contact to the ends of the tubular body, a flanged metallic locking ring applied to the facing rings by frictional contact within the tube and a disk mounted upon each flanged locking ring between the flange thereof and the tube facing rings and in facial contact therewith.

7. In a spool construction, in combination, a cylindrical tubular body, metallic facing devices applied to the ends of the tube by frictional contact therewith, metallic locking devices applied to the metallic facing devices within the tube by frictional contact and a pasteboard spool flange carried by each metallic locking device.

WALTER L. RUTKOWSKI. 120
